UNITED STATES PATENT OFFICE.

HENRY E. McMANUS, OF BOGOTA, NEW JERSEY.

GUARD RAIL FOR STATION PLATFORMS.

Application filed December 9, 1924. Serial No. 754,819.

To all whom it may concern:

Be it known that I, HENRY E. McMANUS, a citizen of the United States of America, and a resident of Bogota, in the county of Bergen and State of New Jersey, have invented a new and Improved Guard Rail for Station Platforms, of which the following is a full, clear, and exact description.

This invention has relation to safety devices for station platforms and aims for one of its principal objects to provide means adjacent the edge of subway, elevated or other railway platforms for preventing accidental forcing of waiting passengers over the edge and in the path of moving trains.

At the present time due to congested traffic conditions in the larger cities elevated and subway platforms which are disposed in the same plane with the train floors and platforms, present a dangerous situation to the traveling public when the platforms become over-crowded and the possibility of forcing passengers adjacent the edge of the platform into the path of moving trains.

It is therefore an object of the present invention to provide a guard rail adjacent the edge of a station platform which extends throughout the length thereof and to provide movable sections in said railing connected with means operable by the trains pulling into a station for moving said movable sections to an out-of-the-way position so that the passengers will have free and unobstructed ingress and egress adjacent the doorways of the train.

More specifically the invention comprehends a guard railing having vertically movable sections coinciding with the car doors of a train which are movable through a means actuated by the train to an elevated position to afford a free and unobstructed passageway through the railing for the passengers entering and leaving the doorways.

The invention furthermore comprehends an apparatus of the character set forth which is comparatively simple in its construction and mode of operation, which is highly efficient in its purpose and which may be readily installed at a minimum expense.

With the above recited and other objects in view, the invention resides in the novel construction set forth in the following specification, particularly pointed out in the appended claims and illustrated in the accompanying drawings, it being understood that

the right is reserved to embodiments other than those actually illustrated herein, to the full extent indicated by the general meaning of the terms in which the claims are expressed.

In the drawings

Figure 1 is a fragmentary view partly in section and partly in elevation illustrating the safety guard means installed on a station platform and showing respectively in full and dotted lines the closed and open condition of the same.

Fig. 2 is a fragmentary plan view thereof illustrating the train actuating means in its active and inactive positions in full and dotted lines.

Referring to the drawings by characters of reference 10 designates a station platform of the type which is disposed in the same plane with the car floors and platforms and in which the road-bed is in a lower or sunken plane. In accordance with the present invention the platform is provided with a railing 11 approximately waist high which is supported adjacent the edge of the platform by standards or uprights 12. The railing 11 is provided with vertically movable sections 13 disposed adjacent the points where the car doors of the train are positioned when the train is stopped at the platform for receiving and discharging passengers. The railing sections 13 are each connected with a depending plunger rod 14 which has secured to its lower end a plunger or piston 15 movable in a cylinder 16 which cylinder is mounted vertically of the platform and adjacent the edge thereof and approximately midway between the spaced ends of the stationary guard rail sections 11. The movable guard rail sections 13 are vertically apertured adjacent their opposite ends as at 17 to receive the vertical guide rods 18 which are connected to the platform and if desired to an overhead support or ceiling 19. The lower end of the cylinder 16 has communicating therewith a fluid conduit 20 which leads to a suitable source of fluid supply such as compressed air or the like. The conduit 20 has arranged therein a valve 21 of any approved type the core of which is connected with an actuating arm 22 whereby when the arm is swung in one direction communication is established through the conduit from the fluid supply to the cylinder 16 and when moved to another position said communication is cut off. Alongside the

21

platform 10 a laterally movable bar 23 is mounted for movement toward and away from the side of the platform and suitable means such as springs 24 are employed for normally forcing the bar 23 outwardly away from the platform a limited distance. The opposite ends 25 of the bar 23 are curved inwardly toward the platform to provide a ramp or cam surface with which the forward end of the forward car of a train is designed to coact for moving the bar 23 laterally inward to the dotted line position illustrated in Fig. 2, against the action of the springs 24. The bar 23 is connected by a connecting rod 26 with the free end of the arm 22 of the valve core and said valve core is so arranged that when the bar 23 is depressed inwardly and the arm 22 is swung to the position illustrated in dotted lines in Fig. 2, communication will be established through the conduit 20 between the source of fluid supply and the cylinder 16.

From the foregoing it will thus be seen that when a train pulls into a station and alongside of the platform 10 the lateral inward depression of the bar 23 toward the platform will operate the valve 21 to admit the compressed air or other operating fluid into the cylinder 16. The fluid admitted into the cylinder 16 will act against the plunger or piston 15 and consequently elevate the movable guard rail sections 13 to afford a free and unobstructed passageway coincident with the car doorways of a train whereby the passengers may readily gain access to or egress from the cars. When the train leaves the station and the springs 24 return the bar 23 to normal laterally distended relation the arm 22 is swung to a position to move the valve core to a position to cut off communication of the source of supply of compressed air or fluid to the cylinder 16 and the weight of the guard rail sections 13, the plunger rods 14 and plungers or pistons 15 will act to effect the lowering of the guard rail sections 13 to normal position in alignment with the stationary guard rail sections 11. It is of course to be understood that the pistons or plungers 15 are sufficiently loose in the bores of the cylinders 16 to permit a gradual gravitational lowering of the movable guard rail sections. In order to arrest the downward movement of the guard rail sections the plunger rods 14 are provided with stop enlargements 27 which engage the upper end of the cylinders 16.

In order to control the flow of fluid from the valve 21 to the cylinder 16 a regulating valve 28 is provided in the conduit 20.

From the foregoing it will thus be seen that an extremely simple yet highly efficient safety apparatus for elevated railway station platforms has been provided which apparatus is automatic in operation.

I claim:

1. A safety apparatus for railway station platforms comprising guard means provided adjacent the outer edge of the platform and extending throughout the length of the same, said guard means having longitudinally spaced passageways therethrough with which the doorways of the cars of the train coincide when the train is stopped at the platform for the reception and discharge of passengers, movable barriers normally closing said passageways and means operable by the train pulling into the platform for elevating the barriers to and maintaining the same in said elevated out-of-the-way position while the train is stopped at the platform and means operable when the train pulls away from the station to release the barriers whereby they gravitationally move to a normal position for obstructing the passageways.

2. A safety apparatus for railway station platforms comprising guard means provided adjacent the outer edge of the platform and extending throughout the length of the same, said guard means having longitudinally spaced passageways therethrough with which the doorways of the cars of the train coincide when the train is stopped at the platform for the reception and discharge of passengers, movable barriers normally closing said passageways and means operable by the train pulling into the platform for elevating the barriers to and maintaining the same in said elevated out-of-the-way position while the train is stopped at the platform and means operable when the train pulls away from the station to release the barriers whereby they gravitationally move to a normal position for obstructing the passageways, said means comprising a cylinder mounted vertically and centrally of each passageway, a piston axially movable in the cylinder and connected with the barrier, a fluid conduit communicating with the cylinder and a source of supply, a valve in the conduit between the cylinder and source of supply, valve opening and closing means and means connected with the valve opening and closing means operable by contact with a train for opening the valve operating means.

3. A safety apparatus for railway station platforms comprising guard means provided adjacent the outer edge of the platform and extending throughout the length of the same, said guard means having longitudinally spaced passageways therethrough with which the doorways of the cars of the train coincide when the train is stopped at the platform for the reception and discharge of passengers, movable barriers normally closing said passageways and means operable by the train pulling into the platform for elevating the barriers

to and maintaining the same in said elevated out-of-the-way position while the train is stopped at the platform and means operable when the train pulls away from the station to release the barriers whereby they gravitationally move to a normal position for obstructing the passageways, said means comprising a cylinder mounted vertically and centrally of each passageway, a piston 10 axially movable in the cylinder and connected with the barrier, a fluid conduit communicating with the cylinder and a source of supply, a valve in the conduit between the cylinder and source of supply, valve opening and closing means and means connected with the valve opening and closing means operable by contact with a train for opening the valve operating means, said latter means comprising a laterally depressible bar 20 projecting from the side of the platform, means for normally projecting the platform laterally therefrom and inwardly curved terminals on said bar constituting camming means for engagement with the forward end of a train to depress the same laterally toward the platform.

4. A safety apparatus for railway station platforms comprising guard means provided adjacent the outer edge of the platform and 25 extending throughout the length of the same, said guard means having longitudinally spaced passageways therethrough with which the doorways of the cars of the train coincide when the train is stopped at the platform for the reception and discharge 30 of passengers, movable barriers normally closing said passageways and means operable by the train pulling into the platform for elevating the barriers to and maintaining the same in said elevated out-of- 35 the-way position while the train is stopped at the platform and means operable when the train pulls away from the station to release the barriers whereby they gravitationally move to a normal position for obstructing the passageways, said means comprising a cylinder mounted vertically and centrally of each passageway, a piston 40 axially movable in the cylinder and connected with the barrier, a fluid conduit communicating with the cylinder and a source of supply, a valve in the conduit between the cylinder and source of supply, valve opening and closing means and means connected with the valve opening and closing 45 means operable by contact with a train for opening the valve operating means and means in the conduit between the valve and the cylinder for regulating the flow of fluid therethrough.

HENRY E. McMANUS.
